VENT FAN AND BILGE PUMP

Harry Najimian, Jr., Waukegan, Ill., and Albert E. Buchholz, deceased, late of Kenosha, Wis., by Robert K. Gerling, special administrator, Des Plaines, Ill., assignors to Outboard Marine Corporation, Waukegan, Ill., a corporation of Delaware

Filed Apr. 28, 1961, Ser. No. 107,006

6 Claims. (Cl. 103—6)

This invention relates to a combination bilge pump and ventilator for marine use.

Particularly in boats having closed engine compartments, the presence in the bilge of combustible hydrocarbons such as oil or gasoline is a serious fire hazard increased by the presence of gasoline vapors in the compartment. It is desirable to eliminate both the liquids and the vapors, along with any water which may be in the bilge and to do this with a motor which is not exposed to the explosive vapor.

To these ends, the present invention provides a housing for a double ended motor, the housing being sealed about the motor shell and having sealing openings through which the two ends of the motor armature shaft project into upper and lower chambers. In these chambers the opposite ends of the motor shaft carry impellers respectively designed for liquids and for gases, each such chamber having its own outlet.

A feature of the assembly consists in the construction of the housing, which uses two identical housing components joined centrally in mutually inverted relationship, the two components having cavities which together provide the motor compartment, each section of the housing having its own impeller compartment and tangential discharge port. The cover plates for the respective sections of the housing are interchangeable, desirably screened, and applicable to the respective housing sections in the same manner.

Connection of the respective housing sections to the motor shell not only seals these sections to each other, but also positions the motor in its cavity. The chambers for the respective impellers are, however, desirably eccentric with reference to the axis of the motor armature shaft.

In the drawings:

FIG. 1 is a view in side elevation of a device embodying the present invention.

FIG. 2 is a view taken in section on the line 2—2 of FIG. 1.

FIG. 3 is a plan view.

FIG. 4 is a bottom plan view.

FIG. 5 is a fragmentary detail view in section on line 5—5 of FIG. 3.

The motor M may be of any conventional design. Its armature shaft 5 projects at both ends of its frame or shell 6.

The motor is enclosed in a chamber 7 made by uniting sections 8 and 9 of a housing generically designated by reference character 10. Each of the sections 8 and 9 is provided with a cavity, the two cavities together providing the chamber 7 within which the motor is disposed. Channels 11 and 12 of the respective sections 8 and 9 receive packing 13 incorporated in the assembly of the sections 8 and 9 to exclude water from the chamber 7 in which the motor operates.

The sections 8 and 9 of the housing 10 are identical. However, they are assembled in mutually inverted relationship each provided with a transverse partition at 14 having bosses 15 and 16 against which the motor shell may seat. Studs 17 on the motor shell 6 extend through partitions 14 and have nuts 18 engaging the partitions to

2

connect the housing sections to the motor to position the motor and hold the housing sections together upon packing 13. Packing is desirably provided at 19 in each housing partition 14 around the respective projecting end of the armature shaft 5.

Each housing section has an impeller chamber 20 separated from the motor chamber 7 by the partition 14, in each case. Opening from each such chamber are one or more sleeves 22, preferably tangential. A detachable cover plate 23 closes each impeller chamber 20, and retains a screen 24 which is held in place by the cover plate 23 when the latter is screwed to the housing. Each cover plate is centrally ported at 25.

It will be noted that each chamber 20 is eccentric with reference to the axis of the impeller shaft 5, the eccentricity being designed to facilitate discharge of fluids through one of the tangential outlet sleeves 22. At the upper end of shaft 5 is an impeller 21 of a type suitable for functioning as a blower for the discharge of air and other gases and vapors.

The lower end of the armature shaft 5 also mounts an impeller 30 but this impeller is particularly designed to handle liquids, desirably being of shorter axial extent. The lower chamber 20 and its tangential discharge port or ports (the sleeves 22) are identical with those above described, the housing section being the same part in inverted position. Likewise the cover plate 23 may be identical. However, in this instance, because the axial dimension of the impeller 30 is shorter than that of impeller 21, the impeller 30 does not so nearly fill the chamber.

The wiring 27 leading to the motor M enters one of the housing sections through a hole 28 sealed about the wire by a grommet 29. The corresponding hole at 28' in housing section 9 may be closed by a plug 29', if any such hole exists. Of course if the hole 28 was bored specially in housing section 8, there will be no corresponding hole in housing section 9.

With the motor in operation, both impellers are operated to expel through the upper and lower tangential outlet ports the fluids acted upon by the respective impellers. Provision of two outlets from each chamber facilitates any desired connection of a discharge hose such as those shown at 31 and 32. The unused outlet is closed by a plug, as at 33, 34. Other things being equal, the discharge would be arranged through the outlet toward which the respective rotor turns. However, this is not essential.

As noted, it is ordinarily desirable to ventilate the motor compartment at the same time that the bilge is drained. Accordingly, a single motor used as above described is a convenient means of achieving these two objectives simultaneously.

We claim:

1. The combination of a motor having a supporting shell and a double ended armature shaft, housing means comprising a pair of identical sections, each housing section having an impeller chamber and a motor cavity separated by a partition including an aperture, and means on said shell and on each of said housing sections for securing said sections in mutually engaged, inverted relation to each other to thereby define a substantially closed motor chamber formed by said motor cavities and for supporting said motor within said motor chamber with said armature shaft extending through said apertures.

2. The combination of housing means including sealing means and a pair of identical housing sections each including an impeller chamber and a motor cavity separated by a partition including an aperture, said housing sections being disposed in inverted relation to each other on opposite sides of said sealing means to thereby de-

fine a substantially closed chamber formed by said motor cavities, a motor having a supporting frame and a double ended armature shaft, co-operating means on said frame and on each of said housing sections for securing said sections to said frame to support said frame within said chamber with said armature shaft extending through said apertures and for engaging said housing sections against said sealing means, and packing means in said apertures and around said shaft, whereby said motor chamber is substantially fluidtight.

3. A combination in accordance with claim 2 including a liquid impeller mounted in one of said impeller chambers on one end of said armature shaft, a gas impeller mounted in the other of said impeller cavities on the other end of said armature shaft, and cover plates 15 for the respective impeller chambers.

4. The device of claim 3 in which the respective impellers are of different axial extent, the respective cover plates being centrally ported to provide inlets to said chambers and the respective impellers being proximate 20 the ports of the respective plates despite the difference in axial extent.

5. The device of claim 3 in which each such impeller chamber is eccentric with respect to the motor armature shaft, and has its respective outlet extending from a chamber portion of maximum radius from said armature shaft. 25

6. The device of claim 5 in which each such section has a pair of sleeves projecting oppositely and one of which provides the aforesaid outlet, the other sleeve being provided with a plug detachably engageable selectively with either sleeve.
